UNITED STATES PATENT OFFICE.

FREDERICK DWITT HILL, OF NEW YORK, N. Y.

BURGLAR-ALARM.

SPECIFICATION forming part of Letters Patent No. 325,838, dated September 8, 1885.

Application filed October 9, 1884. (No model.)

To all whom it may concern:

Be it known that I, FREDERICK DWITT HILL, of the city, county, and State of New York, have invented a new and useful Improvement in Burglar-Alarms for Windows, 5 of which the following is a full, clear, and exact description.

Reference is to be had to the accompanying drawings, forming a part of this specification, 10 in which similar letters of reference indicate corresponding parts in both the figures.

Figure 1 is a side elevation of one of my improved burglar-alarms, part being broken away, shown as applied to a window, the window-sashes being shown in section. Fig. 2 is 15 a plan view of the same, partly in section, through the line $x\ x$, Fig. 1, the upper sash and casing of the window being shown in section through the line $x'\ x'$, Fig. 1.

20 The object of this invention is to facilitate the attachment of burglar-alarms to windows and promote reliability in the operation of such alarms.

The invention relates to a burglar-alarm for 25 windows, constructed with an angular plate carrying a clock-work provided with a bell, and having an arm on its escapement-post to engage with a pin attached to a pivoted lever connected by a rod and a band and pulleys with 30 a roller, whereby a movement of the window-sash can be made to spring the alarm. The angular plate carrying the operating mechanism is provided with a flange, with which is connected a clamp, whereby the said alarm can 35 be readily secured to a window-sash, as will be hereinafter fully described.

A represents the casing, B the upper sash, and C the lower sash, of an ordinary window.

D is an angular plate, upon the lower edge 40 of the upper arm of which is formed a laterally-projecting flange, E.

To the flange E are secured two plates, F G. The plate F is secured to the flange E by a rivet, H, and its outer end is bent downward 45 to grasp the rear edge of the top rail of the lower sash, C.

The inner end of the plate F is bent upward, and has a screw, I, rigidly attached to it. The plate G is slotted to receive the screw J, that 50 clamps it to the flange E, so that the said plate can be moved to adjust it to the thick-

ness of the top rail of the lower sash, C, and to clamp and release the said rail. The outer end of the plate G is bent downward to grasp the forward edge of the top rail of the lower sash, C, and its inner end is bent upward, and has an aperture formed through it for the passage of the screw I. The plate G is drawn toward the plate F to clamp the top rail of the lower sash, C, by means of a hand-nut, K, 60 screwed upon the screw I.

To the lower arm of the plate D is attached a clock-work, L, to the escapement-post M of which is attached an arm, N, and the bell-hammer O.

65 The arm N projects into such a position as to engage with a pin, P, attached to the end of an elbow-lever, Q, which is pivoted at its angle to the lower part of the plate D. To the other end of the lever Q is attached one 70 end of a rod, R, the other end of which is pivoted to a crank-pin, S, attached to the pulley T. The pulley T is pivoted to the plate D at its angle, and around the said pulley passes an endless belt, U, which also passes around 75 a pulley, V, formed upon or attached to the roller W. The roller W is pivoted to the end of the upper arm of the angular plate D in such a position that the face of the said roller will project so far as to come in contact with 80 the side rail of the upper sash, B, as illustrated in Figs. 1 and 2, so as to be turned by the friction of the said sash when moved from the position it had when the alarm was set.

85 With this construction, when the alarm has been attached to the sash C and the sashes B C arranged in the desired position, either closed or partly open, the pulleys T V are turned to bring the lever Q into a position that the arm N of the escapement-post M will 90 strike against the pin P of the said lever and hold the clock-work L from operating. When thus arranged, if either sash be moved in either direction, the friction between the sash B and the roller W will move the lever Q, withdrawing the pin P from the arm N and allowing 95 the alarm to sound.

The alarm-bell X' is connected with the frame of the clock-work L or other suitable support.

Having thus described my invention, I claim 100 as new and desire to secure by Letters Patent—

1. A burglar-alarm comprising an attaching-plate, a securing-clamp thereon constructed to engage the top rail of a sash, a bell, a hammer for striking the same, a friction-roller adapted to be operated by the movement of the article to which the alarm is secured, and connections between the friction-roller and the bell-ringing mechanism, substantially as set forth.
2. In a burglar-alarm for windows, the combination, with the angular plate D and a clock-work, L, having an arm, N, attached to its escapement-post M, of the lever Q, having a projecting pin, P, the connecting-rod R, the pulleys and band T V U, and the roller W,

substantially as herein shown and described, whereby a movement of the window-sash can be made to spring the alarm, as set forth.

3. In a burglar-alarm for windows, the combination, with the angular plate D, carrying the operating mechanism and having a flange, E, of the clamp F G I K, substantially as herein shown and described, whereby the said alarm can be readily secured to a window-sash, as set forth.

FREDERICK DWITT HILL
